UNITED STATES PATENT OFFICE.

FRIEDRICH JANUS, OF MUNICH, GERMANY, ASSIGNEE TO SIEMENS & HALSKE, AKTIENGESELLSCHAFT, OF SIEMENSSTADT, NEAR BERLIN, GERMANY, A CORPORATION OF GERMANY.

X-RAY SCREEN.

Application filed April 11, 1924, Serial No. 705,807, and in Germany April 19, 1923.

My invention relates to improvements in X-ray screens for intercepting the secondary rays produced in the body penetrated by the X-rays and rendering in X-ray photography the pictures indistinct.

In known screens of this kind flat bars or strips of a material which is almost impervious to X-rays are used, these bars or strips being arranged edgewise upon a disc-shaped base plate mounted rotatably around its centre. The strips are so disposed that they either point to the centre of rotation or lie spirally around it. In order to prevent the portions of the X-ray plate situated near the circumference from being exposed to the X-rays for longer periods than those situated nearer the centre, the number of radial bars has been increased towards the circumference or the bars have been made wedge-shaped. Both constructions have certain disadvantages, particularly as far as their manufacture is concerned.

It has also been proposed to construct screens of strips of material impervious to X-rays and strips of permeable material, which are combined in layers to form a cylindrical shell. This body is then during the exposure rotated around its cylinder axis. Such screens require a considerable amount of space between the part of the body exposed to the rays and the photographic plate.

In the drawing affixed to my specification and forming part thereof two embodiments of my invention are illustrated by way of example.

In the drawings is:

Fig. 1 a plan of my improved screen,
Fig. 2 a vertical section along line I—I of Fig. 1 and
40 Fig. 3 a plan of a slightly modified construction of the screen.

Similar parts are indicated by the same numerals of reference in all the figures.

Referring to Figs. 1 and 2, it will be seen that the screen has the shape of a circular disc 1 of comparatively small thickness. This disc is supported in three grooved rollers 2 disposed around the circumference. These rollers are fixed upon a suitable frame 3. The circumference of the disc is provided with a groove into which a cord 4 is placed by means of which and a driving pulley 5 provided with a crank 6 and handle also fixed upon the frame 3 the disc is adapted to

be rotated. The ratio of transmission of the 55 cord drive is such that the screen disc can be rotated with a comparatively high speed.

The screen disc is composed of a comparatively large number of sector-like parts or fields 7. Each of these parts consists in itself of a comparatively large number of strips of material pervious to X-rays and other strips of a material impervious to X-rays. These strips consist, for instance, alternately of lead foil and of celluloid, hard 60 paper, bakelite which is a product of condensation of phenol and formaldehyde, or a similar solid material pervious to X-rays. These strips are packed very closely together and are either directly combined into a solid 65 disc by cementing or pasting the strips together or they are fixed upon a base-plate, such as the disc 8 in Fig. 2, which also consists of a material pervious to X-rays and which around its raised edge 9 is provided 70 with the groove for the driving cord 4. In both cases the strips impervious to the X-rays are disposed at right angles to the plane of the disc, whereby the manufacture is 75 greatly simplified.

In the construction illustrated in Fig. 1 the strip composing the individual sector-like parts 7 are so disposed that the central strip is exactly radial to the disc and the other strips are parallel to this strip. In 85 the modification illustrated in Fig. 3 these strips are on the other hand arranged parallel to one edge of the sector-like parts. In each of the fields, the layers or strips of material pervious to X-rays alternate with 90 layers of material substantially impervious to such rays, and all layers of the same field are parallel to each other, but form an angle with the directions of the layers in the neighboring fields.

Although purely theoretically only one single strip of the material impervious to the X-rays is in both cases situated accurately in the direction of the radiation emanating from the X-ray tube, the focus of the tube being assumed to be situated vertically above the centre of the disc, the variations of the shadows caused by the inaccurate position of the other strips in relation to the X-ray tube, are so small that they are no longer 100 perceptible on the X-ray photograph, provided that the strips and the sectors are made sufficiently narrow. The individual sector-

like parts 7 are preferably also made of different width, as illustrated in Fig. 1.

It will be understood that I do not limit myself to the details of construction described and illustrated by way of example, but that these may be varied in many ways, which will easily suggest themselves to those skilled in the art without departing from the spirit of my invention.

10 What I claim as my invention and desire to secure by Letters Patent is:

1. An X-ray screen consisting of a circular disc built up of a plurality of sectors composed of alternate strips of a material pervious to X-rays and of a material substantially impervious to X-rays, the central strip of each sector disposed radially to said disc and the other strips parallel to said central strip, and means for rotating said disc.

15 2. An X-ray screen consisting of a disc mounted to turn and built up of a plurality of sectors each comprising a series of spaced strips made of a material substantially impervious to X-rays, one strip of each sector being radial with respect to the axis about which the disc is mounted to turn, and the other strips of the same sector being parallel to such radial strip.

20 3. An X-ray screen consisting of a disc mounted to turn and built up of a plurality of sectors each comprising a series of spaced strips made of a material substantially impervious to X-rays, the central strip of each sector being radial with respect to the axis about which the disc is mounted to turn, and the other strips of the same sector being parallel to such central strip.

4. An X-ray screen consisting of a flat body mounted to turn and composed of a plurality of individual fields, each of such fields comprising parallel layers of a material substantially impervious to X-rays alternating with parallel layers of a material substantially pervious to X-rays, all of said layers being disposed at right angles to the plane of the screen, and the layers of each individual field extending in a direction at an angle to the directions of the layers in the neighboring fields.

5. An X-ray screen consisting of a disc mounted to turn and composed of a plurality of sectors forming individual fields, each of said sectors comprising parallel layers of a material substantially impervious to X-rays alternating with parallel layers of a material substantially pervious to X-rays, all of said layers being disposed at right angles to the plane of the screen, and the layers of each individual sector extending in a direction at an angle to the directions of the layers in the neighboring sectors.

6. An X-ray screen consisting of a body mounted to turn and composed of a plurality of individual fields, each of such fields comprising spaced parallel strips of a material substantially impervious to X-rays, said strips being arranged edgewise with respect to a plane of rotation, and the strips of each individual field extending in a direction at an angle to the directions of the strips in the neighboring fields.

In testimony whereof I affix my signature.

FRIEDRICH JANUS.
